UNITED STATES PATENT OFFICE.

WALTER L. KEEFER, OF CHAMBERSBURG, PENNSYLVANIA, ASSIGNOR TO THE WOLF CO., OF CHAMBERSBURG, PENNSYLVANIA, A CORPORATION OF PENNSYLVANIA.

VACUUM FLOOR SCRUBBING AND WASHING MACHINE.

Application filed December 17, 1928. Serial No. 681,164.

My invention relates to cleaning machines, having particular relation to floor cleaning machines.

In its broadest aspect, an important object of my invention is to provide a portable, power-driven machine of the class described which is particularly applicable to the scrubbing and cleaning of floors of great area, as found in hotels, factories, public buildings, 10 hospitals and large private residences.

A more specific object of my invention is to provide a scrubbing and washing machine that shall be equally effective for any direction of movement, and that shall use the 15 same cleansing medium over and over again.

Another object of my invention is to provide a scrubbing and washing machine, wherein the cleansing medium on the scrubbed surface is removed and returned 20 through filtering means to the supply tank originally holding the same.

A further object of my invention is to provide a sedimentation chamber in a cleansing medium circulating system which is designed to remove the cleansing fluid from 25 the air, permitting the latter to pass through the fan and associated passages in a substantially dry condition,—the chamber also causing a separation of the heavier foreign 30 matter from the cleansing medium, so that relatively clean fluid may be supplied to the filtering means.

A still further object of my invention is to provide an attachment for the main scrubbing machine in the form of an independently movable scrubbing unit of reduced size which receives its supply of cleansing fluid 35 from the tank of the main machine and which discharges the cleansing fluid removed 40 from the scrubbed surface back into the sedimentation chamber of said main machine.

Although the primary object of my invention is to provide a vacuum scrubbing and washing machine, it is apparent that 45 certain features of my invention are capable of quite general application, as in waxing and polishing machines and also in grinding and polishing machines, all as will be apparent more fully hereinafter.

With these and other objects and applications in mind, my invention further consists in the details of construction and operation hereinafter described and claimed and 50 illustrated in the accompanying drawing, wherein—

Fig. 1 is a top plan view of one form of embodiment of my invention;

Fig. 2 is a side elevational view of the structure of Fig. 1 shown partially in section;

Fig. 3 is a longitudinal sectional view of the structure of the preceding figures, taken on the line III—III of Fig. 1;

Fig. 4 is a longitudinal sectional view of the independently movable scrubbing attachment, and

Figs. 5 and 6 are top plan and side elevational views, respectively, of the structure of Fig. 4.

In the illustrated form of embodiment of 70 my invention shown in Figs. 1, 2 and 3, a supporting framework 1 comprises a horizontally positioned platform 2 and depending side and end portions 3, the latter defining a chamber 5 at one end of the horizontal platform 2 and also providing supports for a pair of centrally positioned 75 wheels 6. The forward end portion of the supporting framework 1 may be further supported by a pair of caster wheels 7.

A scrubber 8 of annular form is mounted within the chamber 5, for rotative engagement with the surface to be cleaned, by means of a supporting gear-wheel 9 which is mounted on a vertically positioned rod 11 having a portion thereof extending up through a perforation 12 in the horizontal plate 2. Relative axial movement between the lower end of the vertical rod 11 and the brush support 9 is avoided by a pin 13 which extends through aligned perforations 14 and 15 in a hub portion 16 of the brush support 9 and in the vertical rod 11, respectively.

The vertically upright rod 11 is revolvably mounted in a cylindrical bushing 17 having an outer surface in threaded engagement with an inner surface of a bushing 18 which is supported in the perforation 12 by a horizontally extending flange 19 adapted to engage the top side of the horizontal supporting plate 2. The lower end of the sleeve 17 is spaced from the hub portion 16 of the brush support 9 by means of a thrust bearing 21 of usual design. The upper end portion of the vertical rod 11 extending beyond the end of the threaded sleeve 17 is provided with an annular member 22 which is secured on the vertical rod 11 by means of a pin 23.

When the threaded sleeve 17 is turned, an 110

axial movement of the rod 11 ensues, causing a corresponding vertical movement of the brush 8. In practice, this adjustable feature is made use of to compensate for the 5 wearing down of the scrubber 8. The brush adjusting sleeve 17 may be secured in a desired position by means of a lock pin 24 which is slidably mounted in a horizontal perforation 25 in the flange portion 19 of 10 the bushing 18, the end of the locking pin 24 being adapted to engage vertical slots 26 formed in the threaded surface of the brush adjusting sleeve 17.

The scrubber 8 may be actuated by means 15 of a motor 29 which is supported on a housing 31 positioned to the rear of the scrubber supporting apparatus on the top side of the horizontal supporting plate 2. A shaft 32 of the motor 29 extends vertically down- 20 wardly into the chamber formed by the housing 31 and it is provided with a pulley-wheel 33 which is operatively associated by means of a belt 34 with a pulley-wheel 35 mounted on a vertical shaft 36 journaled in 25 a bearing 37 supported on the horizontal platform 2. The vertical shaft 36 is provided with a projecting portion 38 which extends through a perforation 39 in the horizontal supporting platform 2, said project- 30 ing portion being provided with gear teeth which are adapted to mesh with the teeth of the supporting gear-wheel 9.

The portion of the horizontal platform 2 to the rear of the brush adjusting mechanism, including that embraced by the pulley 35 wheel 35, the housing 31 and the motor 29, may be enclosed by a rectangular enclosure 42 having front, rear and side walls 43, 44, 45 and 46, respectively. The portion of the 40 enclosed space above the driving mechanism for the scrubber 8, may be formed into a supply tank or chamber 47 for a cleansing medium by a base partition 48, the enclosed space below said base partition 48 having an 45 opening to the outside through perforations 49 formed in the side walls 45 and 46. The cleansing medium, which is contained in the supply tank 47, may be delivered to the inside portion of the scrubbing chamber 5 50 immediately adjacent to the scrubber 8 by means of a supply pipe 50 through a control valve 51, the latter having an operating handle 52 extending out through the rear wall 44.

55 The cleansing medium, which is supplied to the scrubber 8, may be prevented from escaping through the relatively small air gap between the surface to be cleaned and the lower edge of the scrubber housing. 60 formed by the front end portion 3 by creating a vacuum in said scrubber housing. One method of accomplishing this result is shown in Figs. 3 and 4. Referring particularly to Fig. 3, a suction nozzle 53 of arc- 65 uate form opens into the scrubber chamber

5 to the rear of the scrubber 8 and it is spaced a slight distance above the surface being cleansed. The suction nozzle 53 communicates by means of a passage 54 with a sedimentation tank or so-called expansion 70 chamber 55 which is supported from the underside of the horizontal platform 2.

A suction may be created in the nozzle 53 sufficient to cause a relatively large flow of air through said air gap into the vacuum 75 chamber 5, around the edges of the scrubber 8 and into the nozzle 53 by means of a rotary fan or other fluid-propelling means 56 which is mounted on the lower end portion of the driven shaft 32 in the housing 31. 80 Practical experience has shown that said flow of air removes the cleansing medium from the floor surface immediately adjacent to the edges of the scrubber 8, leaving the same clean and substantially dry. The inlet opening of the fan 56 is extended down into the sedimentation chamber 55 by means of a pipe 57 which is carried by the platform 2. The outlet opening of the fan 56 is in the enclosed space below the base partition 90 48 which opens to the outside through the side wall perforations 49.

The supernatant liquid or effluent in the sedimentation tank 55 may be removed therefrom by means of a centrifugal pump 58 and 95 discharged through pipe sections 59, 60 and 61 into the open end of the supply tank 47. The pipe section 59 extends between the pump outlet opening and the pipe section 60, the latter being mounted on a removable 100 cover plate 62 positioned in the rear end of the sedimentation chamber 55. The pipe section 61 extends between the section 60 and the open end of the supply tank 47.

The centrifugal pump 58 is provided with 105 a vertical shaft 63 which extends through a bearing 64 having a horizontally extending circular flange 65 resting on the upper side of the supporting plate 2. The pump 58 may be more rigidly secured in position 110 by means of supporting elements 66 carried by the flange 65. The upper end of the pump shaft 63 is provided with a pulley wheel 67 which is operatively associated by means of a belt 68 with the driving pulley 115 wheel 33.

In order to further screen the used cleansing medium prior to its mixing with that in the supply tank 47, the same is caused to pass through a series of superimposed filtering screens 69 and 70 which are mounted on the upper end of the tank 47. To still further purify the cleansing medium, a body 70' of sand or crushed coke or like purifying material may be interposed between the 120 screens 69 and 70. A suitable handle 71 for moving the machine may be attached to the depending side portion 3. A control button 72 for the driving motor 29 may also be mounted on the handle 71. 125

Assuming the control valve 51 open to permit of a supply of the cleansing medium to the scrubber 8, when the motor control button 72 is closed, the scrubber 8, the rotary fan 56 and the centrifugal pump 58 are simultaneously operated, the rotary fan 56 serving to create a vacuum in the scrubber chamber 5, whereby a relatively large flow of air may be established around the scrubber 8 and drawn up into the nozzle 53. As a result of said flow of air, the cleansing medium on the floor surface not directly under the scrubber 8 is removed, leaving a surface which is clean and substantially dry. The air and fluid drawn up into the nozzle 53 may then be discharged into the sedimentation or expansion chamber 55 where the air expands sufficiently to permit the cleansing medium to be deposited. The relatively dry air, after being freed from the cleansing medium, is now removed from the sedimentation chamber 55 by the rotary fan 56 and discharged from the machine through the side wall perforations 49. The supernatant liquid, which is formed in the sedimentation tank 55, may be removed by means of the pump 58 and discharged through the filtering screens 69 and 70 back into the supply tank 47.

In Figs. 4, 5 and 6 is shown an attachment for the main scrubbing machine above described in the form of an independently movable scrubbing unit which receives its supply of cleansing fluid from the tank 47 of the main machine and which discharges the cleansing medium removed from the scrubbed surface back into the sedimentation chamber 55 of said main machine. The attachment therein shown comprises a casing 73 forming a hollow chamber 74 adapted to receive a scrubber 75, the latter being mounted for vertical adjustment in the general manner shown in the previous figures. The scrubber 75 is directly driven by a pinion 76 of a driving motor 77, the latter being mounted on the upper side of the casing 73 and enclosed by a protective casing 78.

The cleansing medium may be supplied to the scrubber 75 through a flexible pipe 79 adapted to have an operative connection with the main supply pipe 50. The cleansing medium not directly under the scrubber and particularly that adjacent to the outer edges of the scrubber chamber may be removed by creating a vacuum in said scrubber chamber, and this may be effected through a nozzle 80, similar to the nozzle 53 of the main machine. The nozzle 80 is operatively

associated with the sedimentation chamber 55 by means of a flexible pipe 81, the end of which is adapted to be removably inserted through a normally closed opening 83 in the side wall of the sedimentation chamber 55. The further operation of the above-described attachment is the same as that described for Figs. 1, 2 and 3. It will be understood, however, that the fan 56 is of sufficient size and power to supply the quantity of air necessary to produce a vacuum in the nozzle 80 as well as in the nozzle 53, if both nozzles are operated simultaneously or singly. When the scrubber 75 is being used the suction produced in the nozzle 53 will prevent the material delivered into the sedimentation chamber 55 by the pipe 81 from passing downwardly through the pipe 54.

While I have shown but one embodiment of my invention, for the purpose of describing the same and illustrating its principles of construction and of operation, it is apparent that various changes and modifications may be made therein without departing from the spirit and scope of my invention. I desire, therefore, that only such limitations shall be imposed thereon as are indicated in the appended claims or as are demanded by the prior art.

I claim:

1. In combination, a scrubber, a chamber for supplying a cleansing medium to said scrubber, a suction nozzle positioned adjacent to said scrubber, means for creating a suction in said nozzle, means for receiving the discharge from said nozzle and permitting the separation of the air and cleansing medium in said discharge, pumping means interconnecting said second-mentioned means and said supply chamber, and means for actuating said scrubber and said suction and said pumping means.

2. A machine comprising a supporting body movable over a surface to be cleaned, a scrubber, said supporting body including a housing for said scrubber, a suction nozzle opening into said housing, a rotary fan for creating a suction in said nozzle, an expansion chamber carried by said supporting body and adapted to receive the discharge of said nozzle, a tank for supplying liquid to said scrubber, said tank being provided with filtering means, a pump for delivering the supernatant liquid in said expansion chamber to said filtering means, and means for actuating said scrubber, fan and pump.

WALTER L. KEEFER.
